FLUID SEALED PACKING GLAND

Adolf Baumann, Wettingen, Switzerland, assignor to Aktiengesellschaft Brown Boveri & Cie., Baden, Switzerland, a joint-stock company of Switzerland

Application July 10, 1929, Serial No. 377,296
In Germany July 18, 1928

5 Claims. (CL. 62—115)

This invention relates to fluid-sealed packing glands in which the operating medium handled by the device to be sealed is itself used as a sealing medium.

It is often undesirable to use a special sealing medium, such as oil, for installations handling fluids such as is the case in refrigerating installations because of the danger of contaminating the operating medium by contact therewith or because of the formation of the reaction products by the initiation of chemical action between the special sealing medium and the operating medium. Further, such special sealing mediums generally require a separate circulating system which may fail to operate when required and which materially decreases the total reliability of the installation. The use of the fluid operating medium itself for sealing purposes, especially in a refrigerating installation in which it may be taken directly from the compressor therefor, avoids the necessity for a special sealing medium and an auxiliary circulating system.

It is, therefore, one of the objects of the present invention to provide a sealing gland in which the fluid operating medium itself is utilized as the sealing medium.

Another object of the invention is to provide a structure in which the machine to be sealed is itself used as the means for circulating the fluid sealing medium.

Another object of the invention is to provide a structure in which the whole of the fluid operating medium of a fluid handling installation is conducted through a sealing gland for sealing the shaft of the compressor or circulator therefor.

A further object of the invention is to so arrange a refrigerating installation that the packing gland for the compressor shaft is sealed by the refrigerant flowing from the condenser to the vaporizer.

Objects and advantages, other than those above set forth, will be apparent from the following description and the drawing in which;

Figure 1 is a view, partially in section, the sectioned portion being enlarged for purposes of illustration, of one embodiment of the present invention, and

Fig. 2 is a view, partially in cross-section, of a modification of a structure which may be utilized in connection with the embodiment shown in Fig. 1.

Referring more particularly to the drawing by characters of reference, reference numeral 3 indicates a compressor having the casing 4 thereof extended to receive the sealing gland struc-

ture, to be more specifically described hereinafter, through which a shaft 5 extends. The discharge of the compressor 3 is connected by a conduit 6 with a condenser 7 in which the high temperature, high pressure fluid is cooled and thereby, at least, partially liquefied. Condenser 7 is connected by a conduit 8 with the extension of the casing 4 which is provided, at the point of connection with the conduit, with a spacer member 9 arranged about shaft 5 of the compressor, which spacer member separates flexible packings 11 in such manner that a considerable distance is maintained between the packings, thereby forming an annular chamber about the shaft. A conduit 12 forms a discharge passage from the space maintained by spacer member 9 to a vaporizer 13 from which the fluid is returned to compressor 3 by a conduit 14. Conduit 12 is provided with a suitable valve 16, which may be also the pressure reducing valve when employed for the passage of fluid in the so-called "dry" refrigerating systems, which is preferably of the non-return type, and with an intercooler 17, connected between the annular chamber maintained by the spacer 9 and the valve 16 which provides for radiation of the heat absorbed by the fluid in its passage through the several conduits from condenser 7 to vaporizer 13. It will be seen that the main flow of the fluid passes about shaft 5 of the compressor 3, at right angles thereto, assisting in preventing the entrance of air into the compressor. This structure also serves the purpose of cooling the shaft of the compressor, which usually operates at high speed and is continually heated due to the friction between the shaft and its bearings and the packings arranged thereabout. It may be necessary or desirable that only a portion of the operating medium be used as a sealing medium. Such use is also to be understood as within the invention.

As shown in the drawing, the end of the casing extension 4 is closed by a gland 24 and, in order that such small quantities of the refrigerant as may be forced along the shaft from the chamber, maintained by the spacer member 9, may be prevented from escaping through such gland into the atmosphere, a portion of the refrigerant in its liquid high pressure state is bled from the conduit 8 into conduit 18 and circulated therethrough about the vaporizer 13, where it is sub-cooled and discharged through a second annular chamber, maintained about the shaft 5 between the flexible packings 11 by a spacer member 19, into a reservoir 21. Inserted in the conduit 18 is a valve 20 by which the rate and, therefore, the

pressure of the subcooled liquid refrigerant flowing through the chamber, maintained by the spacer member 19, may be regulated to such values as will condense the refrigerant forced 5 thereinto from the chamber, maintained by the spacer member 9, and maintain the space about the refrigerant within the reservoir 21 at substantially atmospheric pressure. For discharging such quantities of refrigerant as may be forced 10 from the chamber maintained by the spacer member 19, towards the end of the casing extension into the reservoir, the gland 24 is provided with a chamber 26 having passages 27 and 28 leading therefrom into the reservoir 21; and a 15 float valve 23 is provided in the reservoir 21 whereby the level of the liquid refrigerant therein and the discharge thereof therefrom through a conduit 22 into the vaporizer 13 is automatically controlled.

20 Instead of providing a spacer member 19 to form the sealing space in the casing extension, a chamber 29 may be formed therein to receive a disk or flange 31 formed or fixed on shaft 5, as shown in Fig. 2. The annular portion of chamber 29 in which flange 31 rotates, maintains the seal by centrifugal action of flange 31 on the fluid contained therein. It will be apparent that such arrangement of sealing flange or disk on the shaft provides for the most complete sealing of 25 the entire packing gland in such manner that loss of fluid along the shaft is minimized.

The use of a special sealing medium and a separate circulating system therefore is accordingly avoided. Further, it will be seen that the 30 danger of contamination of the fluid by contact with air or with a special sealing medium is eliminated and that disturbances during operation due to freezing of a special sealing medium are impossible.

40 Although but one embodiment of this invention has been illustrated and described, it will be understood that various other embodiments are possible, and that various changes may be made without departing from the spirit of the 45 invention or the scope of the claims.

The invention claimed is:

1. In a system of the character described, a rotary compressor having an extension to receive the shaft thereof and being provided with a 50 plurality of chambers arranged therein about said shaft, a condenser, a vaporizer, conduit means connected to form a path for flow of fluid serially through said compressor, condenser, one of said chambers, and vaporizer respectively, an element included in the connection between said one of said chambers and said vaporizer operable to cool said fluid flowing thereinto from said one of said chambers, conduit means connected with the first said conduit means at a point between 55 said condenser and said one of said chambers for withdrawing a portion of said fluid and for discharging the same into another of said chambers, means for cooling said fluid flowing through the second said conduit means before discharging thereof into the said another of said chambers, valve means for regulating the rate of discharge of said fluid into said another of said chambers, and connections forming a path for discharging said fluid from said another of said chambers 60 into said vaporizer, the flow of said fluid through said chambers being operative to seal the said extension against flow of said fluid therefrom by way of said shaft.

2. In combination with a condenser, a vaporizer, and a machine for compressing and con-

tinuously circulating a fluid serially through said machine, condenser and vaporizer, of means for preventing escape of said fluid to the exterior of said machine comprising an extension for the casing of said machine to receive the shaft thereof and having a plurality of chambers arranged therein about said shaft, means for conveying a portion of said fluid from said compressor through one of said chambers to said vaporizer, means for conveying another portion of said fluid in its high pressure liquid state from said condenser through another of said chambers to said vaporizer, and means for regulating the pressure of the portion of said fluid flowing through the said another of said chambers.

3. In combination with a condenser, a vaporizer, and a machine for compressing and continuously circulating a fluid serially through said machine, condenser and vaporizer, of means for preventing escape of said fluid to the exterior of said machine comprising an extension for the casing of said machine to receive the shaft thereof and having a plurality of chambers arranged therein about said shaft, means for conveying a portion of said fluid from said compressor through 100 one of said chambers to said vaporizer, means for conveying another portion of said fluid in its high pressure liquid state from said condenser through another of said chambers to said vaporizer, means for cooling the said another portion of 105 said fluid after leaving said condenser and before flow thereof through the said another of said chambers, and means for regulating the pressure of the said another portion of said fluid flowing through the said another of said chambers.

4. In combination with a condenser, a vaporizer, and a machine for compressing and continuously circulating a fluid serially through said machine, compressors and vaporizer, of means for preventing escape of said fluid to the exterior 115 of said machine comprising an extension for the casing of said machine to receive the shaft thereof and having a plurality of chambers arranged therein about said shaft, means for conveying a portion of said fluid from said condenser 120 through one of said chambers to said vaporizer, means for conveying another portion of said fluid in its liquid high pressure state from said condenser through another of said chambers to said vaporizer, a reservoir included in the connection 125 for conveying the said another portion of said fluid from the said another of said chambers to said vaporizer, valve means included in the connections for conveying the said fluid to the said another of said chambers for regulating the pressure 130 of the said another portion of said fluid flowing through the said another of said chambers into the said reservoir, and a float valve for regulating the flow of said another portion of said fluid from said reservoir into said vaporizer. 135

5. In combination with a condenser, a vaporizer, and a machine for compressing and continuously circulating a fluid serially through said machine, condenser and vaporizer, of means for preventing escape of said fluid to the exterior of 140 said machine comprising an extension for the casing of said machine to receive the shaft thereof and having a plurality of chambers arranged therein about said shaft, means for conveying a portion of said fluid from said compressor 145 through one of said chambers to said vaporizer to cool said shaft and to condense refrigerant vapor flowing from said machine into the said one of said chambers, means for conveying another portion of said fluid in its high pressure liquid 150

state from said condenser through another of
said chambers to said vaporizer to cool said shaft
and to condense refrigerant vapor flowing from
the said one of said chambers into the said an-
5 other of said chambers, valve means for regulat-
ing the pressure of the said another portion flow-
ing into the said another of said chambers, a

sealing gland closing the end of said extension
about said shaft having a chamber therein for
receiving refrigerant flowing from said another
of said chambers, and connections for discharg-
ing refrigerant from the last said chamber into 80
said vaporizer.
